Application February 2, 1946, Serial No. 645,088

19 Claims. (Cl. 62—129)

1

The present invention relates to air conditioning and more particularly to the distribution of refrigerant in the evaporator of a refrigeration system arranged to condition a stream of circulating air.

While the present invention may be applied to other systems it is particularly adapted for use in a refrigeration system of the type illustrated and described in the U. S. Letters Patent to Albert R. Thomas et al. No. 2,282,504, issued May 12, 1942, entitled Refrigeration. In such a system refrigerant flows by gravity from the top to the bottom of an evaporator arranged in a circulating air duct. The evaporator comprises a plurality of substantially horizontal tubes connected in series so that refrigerant flows through each of the tubes in a tortuous path from the top to the bottom of the evaporator. As the air to be conditioned contacts the outside of the evaporator tubes its temperature will be lowered by the transfer of sensible heat to the relatively cold tubes and the air will be dehumidified to a degree dependent upon its wet bulb temperature by cooling a portion of the air below its dew point to condense the water vapor therefrom.

In such an air conditioner it is many times desirable to operate the refrigeration system at less than full capacity to dehumidify the air with minimum cooling. Under such conditions of operation the heat transfer surface of the evaporator remains constant so that all of the refrigerant supplied to the evaporator will be evaporated in the upper half thereof. The moisture removed from the air by contact with the outside of the refrigerated tubes at the upper half of the evaporator then drips onto the unrefrigerated tubes of the lower half and is re-evaporated into the air stream without practically any removal of moisture from the air. As a result the air conditioning system operates to cool the air by evaporative cooling without removing moisture.

One of the objects of the present invention is to distribute refrigerant in the evaporator so that the moisture removed from the air by contact with the outside surfaces thereof will not be re-evaporated into the air stream.

Another object of the present invention is to provide a refrigerant divider for delivering refrigerant to only a part of the evaporator when operating at less than full capacity and delivering refrigerant to the whole of the evaporator when operating at full capacity.

Another object is to provide a refrigerant divider of the type indicated adapted to deliver refrigerant at a predetermined rate to one section

2

of the evaporator and deliver refrigerant supplied in excess of the predetermined rate to another section of the evaporator.

Another object is to provide an evaporator having a plurality of vertical sections with a refrigerant divider for delivering all of the refrigerant to one section at partial load and delivering refrigerant to the other sections successively as the load increases.

Another object is to provide an evaporator having a plurality of sections arranged one above the other and an arrangement for delivering all of the refrigerant to the lower half of the evaporator at partial load and to the upper and lower halves 15 of the evaporator simultaneously at full load to prevent re-evaporation of moisture removed from the air.

Another object is to provide an evaporator through which refrigerant flows by gravity from 20 the top to the bottom thereof and a refrigerant divider or regulator permitting a restricted flow of refrigerant to the middle of the evaporator and an unrestricted flow of any accumulated refrigerant to the top of the evaporator so that all 25 of the refrigerant supplied will be delivered to either the middle or to the top of the evaporator.

Still another object is to provide an evaporator 30 of the type indicated which is of simple and compact construction, adapted for economical manufacture, and operable over long periods of time without requiring repair or replacement of parts.

These and other objects will become more apparent from the following description and drawings 35 in which like reference characters denote like parts throughout the several views. It is to be expressly understood, however, that the drawings are for the purpose of illustration only and not a definition of the limits of the invention, 40 reference being made for this purpose to the appended claims. In the drawings:

Fig. 1 is a diagrammatic view of an absorption refrigeration system incorporating the sectional evaporator and refrigerant divider of the present invention;

Fig. 2 is an enlarged sectional view of the refrigerant divider illustrated in Fig. 1;

Fig. 3 is an enlarged transverse sectional view 50 of a portion of the evaporator showing the tubes arranged in separate vertical rows or sections;

Fig. 4 is a transverse sectional view of an evaporator of modified construction showing the evaporator tubes arranged in upper and lower sections and the connections between adjacent 55 tubes;

Fig. 5 is a sectional view similar to Fig. 4 showing the connections between adjacent tubes at the opposite end of the evaporator;

Fig. 6 is an enlarged view similar to Fig. 4 showing a refrigerant divider of modified construction;

Fig. 7 is a sectional view taken on line 7-7 of Fig. 6 showing the metering device for delivering refrigerant at a predetermined rate from the bottom of the refrigerant divider trough, and

Fig. 8 is a longitudinal sectional view of the metering device taken on line 8-8 of Fig. 7.

Referring to the drawings, the present invention is shown applied to an absorption refrigeration system for conditioning air of the type illustrated and described in the Thomas patent, referred to above. Such a system operates in a partial vacuum and utilizes water as a refrigerant and a salt solution as an absorbent. Suffice it to state herein that the refrigeration system comprises a generator 10, condenser 11, evaporator 12, absorber 13 and heat exchanger 14 interconnected to provide a closed circuit for the circulation of refrigerant and absorbent. The generator 10 has a series of upright tubes 15 connected at their lower end to an inlet chamber 16 for absorption solution and connected at their upper ends to a separating chamber 17. Surrounding tubes 15 is a shell 18 providing a heating chamber 19 therebetween. Separating chamber 17 is connected to the condenser 11 by a conduit 20 and the condenser, in turn, is connected by a U-shaped conduit 21 to the evaporator 12 through a refrigerant divider 21, later to be described in detail. The evaporator 12 communicates with the absorber 13 through passages or headers 22 and the space between the headers constitutes a part of an air duct through which the air to be conditioned is circulated.

Absorption solution weak in refrigerant or, in other words, a concentrated salt solution flows from the separating chamber 17 to the top of the absorber 13 in a path of flow including the conduit 23, heat exchanger 14, and conduit 24. Absorption solution strong in refrigerant or, in other words, dilute solution flows from the bottom of the absorber 13 to the inlet chamber 16 of the generator 10 in a path of flow including the conduit 25, heat exchanger 14, conduit 26, preheating vessel 27 and conduit 28. The generator 10 and condenser 11 are maintained at a higher pressure than the evaporator 12 and absorber 13 by liquid columns in the conduits 21, 24 and 25. In Fig. 1 the liquid level in the conduit 21 is indicated by the reference character X, the liquid level in conduit 23 connected to the conduit 24 through the heat exchanger 14 is indicated by the reference character Y and the liquid level in the conduit 25 is indicated by the reference character Z.

The absorber 13 and condenser 11 are cooled by cooling water from any suitable source such as a city main, cooling tower, or the like. The cooling water is supplied through a conduit 30 to a header 31 which supplies the cooling water to a bank of pipe coils 32 in the absorber 13. The cooling water from the coils 32 is delivered to a header 33 and from the header it flows through a conduit 34 to the inlet chamber 35 of the condenser 11. Cooling water from the condenser 11 is discharged through the conduit 36.

The generator 10 is heated by steam supplied from a boiler 38 through a conduit 39 to the heating chamber 19. The upper end of the heating chamber 19 of the generator 10 is vented to the atmosphere by a vent pipe 40, and condensate

drains from the lower end of the heating chamber through a drain pipe 41. Thus, steam is supplied to the heating chamber 19 of the generator 10 at a predetermined constant pressure and temperature and its heat is transferred through the tubes 15 to heat the absorption solution therein and expel refrigerant therefrom. The rate at which refrigerant is expelled from the absorption solution in the generator 10 is dependent upon the amount of steam supplied to the heating chamber 19 which, in turn, is dependent upon the amount of heat supplied to the boiler 38.

To adapt the refrigeration system to operate at varying capacities a plurality of burners are provided for heating the boiler which are operable singly or jointly. As illustrated, two burners 42, 43 are provided to adapt the system to operate at part capacity when the burner 42 alone is in operation and at full capacity when both burners are in operation. The burners may be controlled in any suitable manner and as herein illustrated they are controlled by fuel valves 44, 45 actuated by electrical means energized in response to the temperature of the ambient to be controlled. Each of the valves 44 and 45 has a magnetic plunger 46 on its valve stem which is actuated by a solenoid 47 to open the valve and by a spring 48 to close the valve. The solenoids 47 for the valves 44, 45 are connected in parallel branch circuits to supply mains S, S1. The branch circuit for the valve 44 includes a conductor 49 connecting the supply main S to one side of the solenoid 47, a conductor 50 connecting the other side of the solenoid to a switch 51 and a conductor 52 connecting the switch to the other supply main S1. The branch circuit for the valve 45 comprises a conductor 53, solenoid 47, conductor 54, switch 55 and conductor 56.

The switches 51 and 55 may be of any suitable construction and for purposes of illustration they are shown as toggles with one arm of the toggle extending into slots 57 and 58 in an operating bar 59 and the arrangement is such that movement of the bar to the right as viewed in Fig. 1 will cause switch 51 to close and energize the solenoid 47 to open the valve 44 and thereafter close the switch 55 to open the valve 45. The bar 59 is actuated by a thermostat comprising a bulb 60 subjected to the temperature of the ambient and an expansible bellows 61 connected by a capillary tube 62. The expansible bellows 61 is connected through a rod 63 to one end of a pivoted lever 64 and the opposite end of the lever extends into a slot 65 in the bar 59. The bulb 60 contains a volatile liquid which increases the pressure therein directly in proportion to increases in temperature to expand the bellows 61 and thereby rock the lever 64 to slide the bar 59 and close the switches 51 and 55 successively. A spring 66 operates the bellows 61 upon a decrease in pressure to rock the lever 64 and slide the bar 59 to open the switches 55 and 51 successively.

In accordance with the present invention the evaporator 12 is divided into separate sections A and B through which refrigerant flows by gravity. The evaporator 12 is located in an air duct through which air is caused to circulate and comprises a series of substantially horizontal tubes 68 extending between the spaced headers 72 with vertical fins 69 connecting the tubes, see Fig. 1. For the purpose of illustration the tubes 68 of the evaporator 12 are shown in the embodiment of the invention illustrated in Fig. 3 as arranged in two vertical rows in parallel side by side relationship to provide the separate sections

A and B, but it is to be understood that each section may include more than a single row of tubes. The ends of the tubes 68 project through the walls of the headers 22 to which they are sealed and refrigerant flowing from the end of each tube of a row or section is directed into the end of the next lowermost tube of the section by a series of cups 70 in the headers. The cups 70 are arranged to receive refrigerant from the ends of alternate tubes in the opposite headers so that they connect the tubes in series for gravity flow of refrigerant through each tube from the top to the bottom of the section.

Between the end of the U-shaped supply pipe 21 and the top of the evaporator 12 is a refrigerant divider or regulator 71 comprising a rectangular box or vessel 72 supported on a vent pipe 73 extending upwardly from one of the headers 22, see Figs. 1 and 2. A septum plate or dam 74 is provided in the vessel 72 to form separate chambers 75 and 76. The end of the U-shaped conduit 21 opens into the vessel 72 above the chamber 75 and a baffle 77 adjacent the end of the conduit 21 directs all of the liquid refrigerant supplied from the condenser 11 into this chamber. Preferably a screen 78 covers the top of chamber 75 to filter out any scale or foreign matter which may be introduced with the refrigerant. A conduit 79 connects the bottom of the chamber 75 to a cup 70 for introducing refrigerant into the uppermost tube 68 of the row of tubes constituting section A of the evaporator, see Figs. 2 and 3. The conduit 79 is provided with a U-shaped bend 80 to provide a liquid trap and a measuring orifice 81 in the trap limits the rate at which refrigerant is delivered from the chamber 75 to section A of the evaporator 12. The measuring orifice 81 is so dimensioned that with a liquid level in the chamber 75 adjacent the top of the dam 74 it will deliver refrigerant continuously at a predetermined constant rate corresponding to operation with one burner to supply refrigerant to substantially all of the tubes 68 of the row or section A. In other words, the coil sections A and B are designed to utilize all of their heat transfer surface to evaporate the refrigerant delivered thereto at full input by both burners 42 and 43 so that all of the surface area of section A will be required to evaporate the refrigerant delivered at half input by one burner. A similar conduit 82 having a trap 83 connects the bottom of the chamber 76 of the refrigerant divider 71 to the other row or section B of tubes 68 of the evaporator. One embodiment of the invention having now been described in detail the mode of operation is explained as follows.

When the control switches 51 and 55 are in the position illustrated in Fig. 1, the refrigeration system is inoperative. As the temperature of the air to be conditioned increases the volatile fluid increases the pressure in the thermostat to expand the bellows 61. As the bellows 61 expands it operates through the rod 63 and lever 64 to slide the bar 59 toward the right as viewed in Fig. 1. Sliding movement of the bar 59 will actuate the toggle switch 51 to closed position and thereby energize the solenoid 47 to open the fuel valve 44 and heat the boiler 38 to generate steam.

Steam generated in the boiler 38 will be supplied through the conduit 39 to the heating chamber 19 of the generator 10 and transmit its heat through the tubes 15 to expel refrigerant vapor from the absorption solution therein. As

the refrigerant vapor is formed it rises in the center of the tubes 19 at considerable velocity and lifts absorption solution at the sides of the tubes by a climbing film action. The refrigerant vapor is separated from the absorption solution in the separating chamber 17 and flows through the conduit 20 to the condenser 11 where it is condensed to a liquid. The liquefied refrigerant flows from the condenser 11 through the U-shaped tube 21 to the refrigerant divider 71. Due to the arrangement of the chamber 75 and the baffle 77 all of the refrigerant supplied from the condenser 11 enters the chamber 75 of the refrigerant divider. The refrigerant entering the receiving chamber 75 is delivered through the conduit 79 to the uppermost tube of the row or section A of tubes 68 in the evaporator 12. As the measuring orifice 81 is of such size as to permit a rate of flow of refrigerant when the liquid level is adjacent the top of the dam 74 corresponding to the amount supplied at part capacity with one burner 42 in operation, all of the refrigerant is supplied to the section A of the evaporator 12.

25 The refrigerant enters one end of the uppermost tube 68 of the evaporator 12 and flows by gravity through each tube in series from the top to the bottom thereof. At the time refrigerant is supplied to the interior of the tubes 68 of the evaporator 12, air is caused to circulate over the exterior of the tubes and fins 69. The heat transfer surface of the tubes 68 of section A is designed to evaporate the amount of refrigerant supplied when the boiler 38 is heated by the single burner 42 so that refrigerant will be supplied to substantially all of the tubes from the top to the bottom of the evaporator section. Furthermore, the interior of the tubes 68 in the evaporator section A are in open communication with the absorber 13 so that the refrigerant in the tubes will evaporate at and have a low temperature corresponding to the pressure in the absorber. Thus, relatively cold tubes 68 of section A of the evaporator 12 extend over the entire cross-sectional area of the air stream, see Fig. 1. The portion of the air directly contacting the outside of the relatively cold evaporator tubes will be cooled below its dew point so that moisture will be condensed thereon to dehumidify the air. The moisture removed from the air will drip from tube to tube from the top to the bottom of section A of the evaporator 12 where it will be drained to a waste pipe, not shown. Due to the fact that substantially all of the tubes 68 of the section A are supplied with refrigerant and relatively cold, the moisture removed from the air will not be re-evaporated into the air stream as it drips from tube to tube to the bottom of the evaporator.

60 As the heat is transferred from the stream of air to the refrigerant in the evaporator tubes 68, the refrigerant evaporates therein and the refrigerant vapor is absorbed in the absorber 13. Absorption solution is continuously supplied to the absorber 13 from the generator 10 in a path of flow from the separating chamber 17 through the conduit 23, heat exchanger 14, and conduit 24 to the top of the absorber where it is distributed and flows downwardly over the bank of coils 32 therein. The spreading of the absorption solution over a relatively large surface area on the banks of coils 32 promotes the absorption of refrigerant vapor as it flows from the ends of the tubes 68 and through the headers 22 to the absorber. The absorption solution enriched with

65

70

75

absorbed refrigerant then flows from the bottom of the absorber through the conduit 25, heat exchanger 14, conduit 26, preheating leveling pot 27 and conduit 28 to the inlet chamber 16 at the base of the generator 10.

The refrigeration system continues to cool and dehumidify the air as it flows over the evaporator 12. If the temperature of the air continues to rise the bellows 61 of the thermostat continues to expand and slide the bar 59 further to the right as viewed in Fig. 1 to close the switch 55. When the switch 55 is closed the second electric branch circuit including the solenoid 47 is energized to open the valve 45 and initiate operation of the burner 43. The refrigeration system then operates at full capacity and the increased amount of steam generated in the boiler 38 and delivered to the generator 10 increases the amount of refrigerant expelled in the generator tubes 18, condensed in the condenser 11 and supplied to the chamber 75 in the refrigerant divider 71. As the refrigerant is supplied to the chamber 75 at a faster rate than it is delivered through measuring orifice 81 in the conduit 79, the refrigerant will flow over the dam 74 into the chamber 76. Refrigerant then will flow from the chamber 76 through the conduit 82 to the top of the other section B of the evaporator 12. The refrigerant flows by gravity through each of the tubes 68 of section B of the evaporator 12 in succession in the same manner as explained with respect to the section A to further cool and dehumidify the air passing over the evaporator tubes.

The refrigeration system will continue to operate at full capacity until the air is cooled sufficiently to decrease its temperature. Upon decrease in the air temperature the spring 66 compresses the bellows 61 of the thermostat and operating through the rod 63 rocks the lever 64 to slide the control bar 59 toward the left as viewed in Fig. 1 to first open the switch 55 to cut out the burner 43 and thereafter open the switch 51 to cut out the burner 42.

Thus, the refrigerant divider 71 receives all of the refrigerant supplied from the condenser 11 and delivers refrigerant to section A of the evaporator 12 at predetermined rate corresponding to the heat transfer surface of the section and delivers all refrigerant supplied in excess of the predetermined rate to section B of the evaporator whereby to insure refrigeration in each tube of section A.

In accordance with the present invention the evaporator may be divided into vertical sections as illustrated and described in connection with Figs. 1 and 3 or the evaporator may be divided into the upper and lower sections as illustrated in Figs. 4 and 5. In the embodiment of the invention illustrated in Figs. 4 and 5, the evaporator tubes 68 are all connected in series both laterally and vertically so that refrigerant supplied to the uppermost tube will flow by gravity through each tube successively to the lowermost tube. The uppermost tube 68, see Fig. 4, is supplied with refrigerant from a cup 70. The refrigerant flows lengthwise through the tube 68 into a cup 70a at the opposite end of the evaporator, see Fig. 5, which directs it into the next laterally adjacent tube 68a arranged at a slightly lower level than the first tube. The refrigerant flowing from the end of the second tube 68a is delivered into a cup 70b which, in turn, directs it into the next adjacent or third lateral tube 68b, see Fig. 4. From the opposite end of the third tube

68b the refrigerant enters a cup 70c which directs the refrigerant into the next or fourth laterally adjacent tube 68c. From the end of the last tube the refrigerant enters a cup 70d which is connected to a cup 70e directly below the first mentioned cup 70 by a pipe 84, see Fig. 4. The refrigerant then flows through the next lateral row of tubes in the manner previously described and from that to the next lowermost row throughout the length of the evaporator.

In this embodiment of the invention the conduit 79 delivers refrigerant from the chamber 75 to an end cup 70f part way between the top and the bottom of the evaporator 12. Similarly the conduit 82 delivers refrigerant from the chamber 76 of the refrigerant divider 71 to the uppermost cup 70 of the evaporator 12. Thus, at part load all of the refrigerant is delivered for flow through the lower section of the evaporator only and at full load the refrigerant is delivered for flow through the upper and lower sections of the evaporator simultaneously. Therefore, at part load any moisture condensed from the air stream will drip over the relatively cold tubes 68 at the lower section of the evaporator 12 and be drained therefrom without re-evaporation into the air stream. However, at full load both the upper and lower sections of the evaporator 12 will be effective to cool and dehumidify the air.

In Figs. 6 to 8 a modified construction of refrigerant divider or flow regulator is shown applied to an evaporator 12 similar to that illustrated in Fig. 4. However, the two uppermost tubes 68 and 68a of the evaporator illustrated in Fig. 6 constitute flash chambers into which refrigerant is delivered from branches 21a and 21b of the U-shaped conduit 21. The refrigerant flows through the flash tubes into a trough or vessel 85 in the rearward header 22. As illustrated in Fig. 6, the bottom 86 of the trough 85 is inclined downwardly and the trough encloses the first three laterally adjacent tubes 68, 68a and 68b. The third and fourth tubes 68b and 68c of the first lateral row of tubes are connected by a cup 70c in the manner described with respect to the evaporator illustrated in Figs. 4 and 5 and the remaining tubes are also connected in a like manner. A delivery conduit 87 connects the lowest point of the bottom wall 86 of the trough 85 to a metering device 88. The metering device 88 comprises an inlet chamber 89 to which the delivery pipe 87 is attached, see Fig. 8, a septum 90 having a measuring orifice 91 therein and an outlet chamber 92 above the septum. Preferably, a cylindrical screen 93 is provided in the inlet chamber 89 through which the refrigerant passes before entering the measuring orifice 91. A conduit 94, see Fig. 7, connects the outlet chamber 92 to a cup 70f midway between the top and the bottom of the evaporator as in the form of evaporator illustrated in Figs. 4 and 5.

The form of refrigerant divider or regulator 71 illustrated in Figs. 6 to 8 operates in a manner similar to the form illustrated in Figs. 4 and 5 in that refrigerant is supplied to the trough 85 and is delivered at a predetermined rate for flow to the lower part of the evaporator 12. When refrigerant is supplied at a faster rate than it is delivered through the measuring orifice 91 it backs up in the trough 85 and overflows into the end of the third tube 68b. Refrigerant entering the third tube 68b then flows through the upper part of the evaporator 12. Thus, at part loads refrigerant is supplied to the lower section of the evaporator only and at full load refriger-

ant is supplied simultaneously to the upper and lower sections. With such an arrangement, moisture removed from the air at partial operating capacity will not be reevaporated into the air stream. The orifice 91 provides a restricted path of flow for refrigerant to the lower half of the evaporator while the tube 68b provides an unrestricted path of flow to the top of the evaporator for any accumulated refrigerant rising in the vessel 85 to the level of the tube. Thus, if the orifice 91 should become plugged or if for any other reason the refrigerant does not flow properly to the lower half of the evaporator, the refrigerant will then flow through the unrestricted tube 68b to the top of the evaporator so that all of the refrigerant supplied from the condenser will be delivered to the evaporator through one or the other of the two paths of flow.

It will now be observed that the present invention provides a novel construction and arrangement of elements to adapt refrigerant to be supplied to one section of an evaporator only at partial load and to a plurality of sections at full load whereby to prevent moisture removed from the air stream from being re-evaporated therein. It will further be observed that the present invention provides a refrigerant divider for supplying refrigerant at a predetermined rate to one of the sections and delivering all refrigerant supplied in excess of the predetermined rate to another section of the evaporator. It will still further be observed that the present invention contemplates the division of the evaporator into a plurality of vertical sections or a plurality of horizontal sections arranged one above the other.

While several embodiments of the invention are herein described, it is to be understood that further modifications may be made in the construction and arrangement of the elements without departing from the spirit and scope of the invention. For example, instead of dividing the evaporator and refrigerant divider into two sections it may be divided into a greater number of sections so as to successively bring in additional sections as the load increases. Therefore, without limiting myself to this respect, I claim:

1. In an absorption refrigeration system of the type which operates in a partial vacuum and utilizes water as a refrigerant and a salt solution as an absorbent, an evaporator having a plurality of sections through which refrigerant flows by gravity, means for supplying refrigerant, a refrigerant divider above the evaporator and adapted to receive refrigerant from the supplying means, a connection between the refrigerant divider and one section of the evaporator for delivering refrigerant thereto at a predetermined rate, and another connection between the divider and another section of the evaporator for delivering refrigerant thereto when the liquid in the divider rises above a predetermined level.

2. In an air conditioner, a refrigerant evaporator having a series of vertical sections arranged in side by side relationship in an air duct, means for supplying liquid refrigerant at varying rates for partial and full load conditions corresponding to the cooling capacity of the separate sections, and a refrigerant divider for receiving all of the liquid refrigerant from the supplying means and having a conduit with a restriction therein to deliver all of the refrigerant to one of the evaporator sections at partial load to dehumidify the air by cooling at least a portion of the air below its dew point, and said refrigerant divider having an unrestricted conduit

operable to deliver accumulated refrigerant to another section of the evaporator at full load whereby substantially the entire surface of said one section is supplied with refrigerant at partial load to prevent re-evaporation of moisture removed from the air.

3. In an air conditioner, a refrigerant evaporator for dehumidifying the air to be conditioned by cooling at least a portion of the air below its dew point, said evaporator having a plurality of vertical rows of substantially horizontal tubes, the tubes of each row being connected to permit refrigerant to flow therethrough by gravity, means for supplying liquid refrigerant, and a refrigerant divider comprising a vessel for receiving the refrigerant from the supplying means, a restricted connection between the vessel and the uppermost tube of one of the rows of evaporator tubes for delivering liquid refrigerant thereto at a predetermined rate sufficient to insure a supply of refrigerant to substantially all of the tubes of the row, and an unrestricted connection between the vessel and the uppermost tube of another row of tubes for delivering liquid refrigerant thereto when the liquid in the vessel rises to a predetermined level whereby to prevent re-evaporation of moisture removed from the air when the conditioner operates at less than full capacity.
4. In an air conditioner, a refrigerant evaporator for dehumidifying air to be conditioned by cooling at least a portion of the air below its dew point, said evaporator having a plurality of vertical rows of substantially horizontal tubes, said tubes of each row being connected to permit refrigerant to flow therethrough by gravity, a refrigerant divider having a vessel with a partition wall therein to divide it into separate chambers, means for supplying liquid refrigerant at different rates for operation at part and full capacity to one of the chambers, a connection between said one chamber and the uppermost tube of one of the rows of evaporator tubes for delivering liquid refrigerant by gravity flow at a predetermined rate sufficient to insure a supply of refrigerant to substantially all of the tubes of the row, and an unrestricted connection between the other chamber of the vessel and the uppermost tube of another row of tubes for delivering refrigerant overflowing the partition wall into the second chamber by gravity flow whereby to prevent re-evaporation of moisture removed from the air by the said one row of tubes when refrigerant is supplied at part capacity.
5. In an air conditioner, a refrigerant evaporator for dehumidifying air by cooling at least a portion of the air below its dew point, said evaporator having a plurality of sections arranged one above the other and connected in series so that refrigerant may flow continuously through successive sections, means for supplying liquid refrigerant at varying rates, and a refrigerant divider for receiving the refrigerant from the supplying means and having a conduit for delivering refrigerant at a predetermined rate corresponding to the cooling capacity of the lower section to the top thereof for flow therethrough by gravity, and said refrigerant divider having a second conduit for delivering all refrigerant supplied over the predetermined rate to the top of the upper section for flow through successive sections by gravity, whereby to prevent re-evaporation of moisture removed from the air during operation of the unit at partial capacity.
6. In an air conditioner, a refrigerant evapo-

11

rator for dehumidifying air by cooling at least a portion of the air below its dew point, said evaporator having a plurality of substantially horizontal tubes connected to each other to permit refrigerant to flow through each of the tubes in series from the top to the bottom of the evaporator, means for supplying liquid refrigerant at varying rates, and a refrigerant divider having a vessel for receiving all of the liquid refrigerant from the supplying means, a restricted connection between the refrigerant divider vessel and the evaporator for delivering refrigerant to an intermediate point of the evaporator for gravity flow through the lower portion thereof at a predetermined rate corresponding to the cooling capacity of said portion, and an unrestricted connection between the refrigerant divider vessel and the top of the evaporator for delivering refrigerant thereto when the refrigerant rises to a predetermined level in the vessel whereby only the lower portion of the evaporator is cooled at partial capacity to prevent re-evaporation of moisture removed from the air and all refrigerant not delivered to the lower section is delivered automatically to the upper section.

7. In an air conditioner, a refrigerant evaporator for dehumidifying air by cooling at least a portion of the air below its dew point, said evaporator having a plurality of substantially horizontal tubes connected to each other to permit refrigerant to flow through each of the tubes in series from the top to the bottom of the evaporator, a refrigerant divider having a vessel with a partition wall therein to divide it into separate chambers, means for supplying liquid refrigerant at different rates to one of the chambers for operation at part and full capacity, a restricted connection between said one chamber and the evaporator for delivering refrigerant to an intermediate point of the evaporator for gravity flow through the lower part thereof at a predetermined rate corresponding to the cooling capacity of said part, and an unrestricted connection between the other chamber and the top of the evaporator for delivering refrigerant overflowing the partition wall for gravity flow through the upper part of the evaporator whereby to prevent re-evaporation of moisture removed from the air at partial capacity.

8. In an air conditioner, a refrigerant evaporator for dehumidifying air by cooling at least a portion of the air below its dew point, said evaporator having a plurality of substantially horizontal tubes, means for connecting groups of the tubes to provide separate sections, a conduit for supplying liquid refrigerant at varying rates to one end of at least one of the tubes for gravity flow therethrough, a vessel at the opposite end of the tube for receiving refrigerant flowing through said tube, a connection from the bottom of said vessel to one section of the evaporator for delivering refrigerant at a predetermined rate corresponding to its cooling capacity for gravity flow therethrough, and a tube connected to said vessel at a level above the first mentioned connection for delivering refrigerant for gravity flow through another section of the evaporator when the liquid rises to a predetermined level in the vessel whereby to prevent reevaporation of moisture removed from the air when the conditioner operates at less than full capacity.

9. In an air conditioner, a refrigerant evaporator for dehumidifying air by cooling at least a portion of the air below its dew point, said evap-

12

orator having a plurality of substantially horizontal tubes, means for supplying refrigerant at different rates to operate the air conditioner at part or full capacity, a conduit connected to one end of at least one of the tubes for delivering the refrigerant for gravity flow therethrough, the remainder of the tubes being connected to permit refrigerant to flow through each tube by gravity from the top to the bottom of the evaporator, a vessel connected to the opposite end of the first mentioned tube for receiving refrigerant flowing therefrom, a connection from the bottom of said vessel to an intermediate point of the evaporator for delivering refrigerant for gravity flow through the lower portion thereof at a predetermined rate corresponding to the cooling capacity of said portion, and a tube connected to said vessel above the bottom thereof for delivering refrigerant to the upper portion of the evaporator when the liquid rises to a predetermined level in the vessel for operation at full capacity whereby to prevent reevaporation of moisture removed from the air during operation at partial capacity.

10. In an air conditioner, a refrigerant evaporator for dehumidifying air by cooling at least a portion of the air below its dew point, said evaporator having a plurality of substantially horizontal tubes, means for supplying refrigerant at different rates for operation at part or full capacity, a conduit connected to one end of at least one of the tubes for delivering the refrigerant for gravity flow therethrough, the remainder of the tubes being connected to adapt refrigerant to flow through each of the tubes in series from the top to the bottom of the evaporator, a vessel connected to the opposite end of the first mentioned tube for receiving refrigerant flowing therethrough, a connection between the bottom of the vessel and an intermediate point of the evaporator, a metering orifice in said connection for permitting the flow of refrigerant to said intermediate point of the evaporator for gravity flow through the lower section of tubes at a predetermined rate corresponding to the cooling capacity of said section, and said vessel connecting said first tube to an adjacent tube at a point above the bottom for delivering refrigerant for gravity flow through the upper section of tubes when the liquid rises to a predetermined level in the vessel whereby to prevent reevaporation of moisture removed from the air during operation at part capacity.

11. In a refrigeration system, an evaporator comprising a plurality of substantially horizontal tubes through which refrigerant flows by gravity, means for supplying liquid refrigerant to one end of at least one of the uppermost tubes, the ends of the remainder of the tubes being connected in series to adapt refrigerant to flow from the top to the bottom of the evaporator, a vessel at the opposite end of the first mentioned tube for receiving refrigerant flowing therefrom, a connection from the bottom of said vessel to a tube intermediate the top and bottom thereof, said connection restricting flow to deliver refrigerant at a predetermined rate for gravity flow through the lower part of the evaporator, and one end of the tube adjacent the uppermost tube being connected to the vessel above the bottom thereof for delivering refrigerant to the upper portion of the evaporator when the liquid rises to a predetermined level therein whereby to cool only the lower portion of the evaporator at partial load and both the upper and lower portions at full load and insure delivery of all of the re-

frigerant to either the upper or lower sections of the evaporator.

12. In an air conditioner, a cooling element for cooling and dehumidifying the air by cooling at least a portion of it below its dew point, said cooling element having a plurality of separate sections contacted by the air, means for supplying cooling medium at varying rates, and a liquid divider for receiving all of the cooling medium supplied and continuously delivering the cooling medium to one of the sections at a predetermined rate corresponding to the cooling capacity of said section and thereafter delivering all excess cooling medium to another section so that the entire surface of said one evaporator section will be cooled to maintain all moisture condensed thereon at a temperature below the dew point of the air to prevent reevaporation.

13. In an air conditioner, a refrigerant evaporator for cooling and dehumidifying air by cooling at least a portion of it below its dew point, said evaporator having a plurality of separate sections contacted by the air to be conditioned, each of said sections having overlying portions so that moisture condensed on one portion will drip onto the next lowermost portion from the top to the bottom of the section, means for supplying refrigerant at varying rates, and a refrigerant divider for receiving all of the refrigerant supplied and continuously delivering the refrigerant to one of the sections at a predetermined rate corresponding to the cooling capacity of said section and thereafter delivering all excess cooling medium to another section so that all portions of said one section will be cooled to maintain moisture condensed thereon at a temperature below the dew point of the air as it drips from successive portions to prevent reevaporation.

14. In an air conditioner, a refrigerant evaporator for cooling and dehumidifying air by cooling at least a portion of it below its dew point, said evaporator having a plurality of separate sections for cooling air directly contacting the same, means for supplying liquid refrigerant at varying rates, a refrigerant divider connected to receive all of the liquid refrigerant from the supplying means, a first conduit connecting the refrigerant divider to one of the evaporator sections to continuously deliver refrigerant to the latter, said conduit having an internal construction to limit the flow of refrigerant to a predetermined rate corresponding to the evaporative capacity of said section, a second unrestricted conduit connecting the refrigerant divider and another section of the evaporator, and means in the divider to limit flow to said first conduit until the refrigerant supplied exceeds the predetermined rate of flow therethrough.

15. In an air conditioner, a refrigerant evaporator for cooling and dehumidifying air by cooling at least a portion of it below its dew point, said evaporator having a series of substantially horizontal tubes arranged one over the other, the tubes being arranged in sections so that refrigerant may flow through the tubes of each section in series, means for supplying refrigerant at varying rates, and a liquid divider for receiving all of the refrigerant supplied and continuously delivering the refrigerant to one of the sections at a predetermined rate corresponding to the cooling capacity of said section and thereafter delivering all excess refrigerant to another section so that all of the tubes of said one section will be cooled to prevent reevaporation of con-

dense into the air stream as it drips over successive tubes from the top to the bottom of the section.

16. In an air conditioner, a refrigerant evaporator for cooling and dehumidifying air by cooling at least a portion of it below its dew point, said evaporator having a plurality of separate sections contacted by the air to be conditioned, means for supplying refrigerant at varying rates, 5 a refrigerant divider comprising a vessel for receiving the refrigerant from the supplying means and having a conduit with a restriction therein to continuously deliver refrigerant to one of the evaporator sections at a predetermined rate corresponding to its evaporative capacity, and said refrigerant divider having a second unrestricted conduit connected to deliver refrigerant to another section when the refrigerant rises above a predetermined level in said vessel.
17. In an air conditioner, a refrigerant evaporator for cooling and dehumidifying air by cooling at least a portion of it below its dew point, said evaporator having a plurality of separate sections contacted by the air, means for supplying refrigerant at varying rates, a refrigerant divider for receiving the refrigerant from the supplying means, a conduit between the liquid divider and one of the sections of the evaporator and having a metering orifice therein for continuously delivering refrigerant from the divider to the evaporator section at a predetermined rate corresponding to the evaporative capacity of said section, and another conduit between the divider and another section of the evaporator for 25 delivering to the latter all refrigerant supplied in excess of the predetermined amount delivered to the one section through the metering orifice.
18. In an air conditioner, an absorption refrigeration system having a generator, a condenser, an evaporator and an absorber interconnected for the circulation of refrigerant and absorbent therein, means for varying the rate at which heat is supplied to the generator to vary the rate at which liquid refrigerant is delivered 30 from the condenser, said evaporator having a plurality of sections through which refrigerant flows by gravity for cooling and dehumidifying air by cooling at least a portion of it below its dew point, a refrigerant divider connected between the condenser and evaporator for receiving all of the refrigerant supplied from the condenser and having a connection for delivering refrigerant to one of the evaporator sections at a predetermined rate corresponding to the evaporative capacity of said section, and said refrigerant divider having a connection for delivering refrigerant to another section of the evaporator when the rate of supply thereto exceeds the predetermined 35 rate at which refrigerant is delivered to said one section.
19. In an air conditioner, a vacuum type absorption refrigeration system utilizing water as a refrigerant and a salt solution as an absorbent and having an evaporator cooled by the evaporation of refrigerant therein to a temperature above freezing, said evaporator having a plurality of separate sections for cooling and dehumidifying air by cooling at least a portion of it below its dew point, means for supplying refrigerant at varying rates, and a liquid divider for receiving all of the refrigerant supplied and continuously delivering refrigerant to one of the sections at a predetermined fixed rate corresponding to the 45 cooling capacity of said section and thereafter 50 55 60 65 70 75

15

delivering all excess refrigerant to another section so that the entire surface of said one evaporator section will be maintained at a temperature below the dew point of the air to prevent reevaporation of moisture condensed thereon.
